CRIMPING MACHINE

Jesse M. White, Philadelphia, Pa.

Application October 8, 1935, Serial No. 43,994

5 Claims. (Cl. 153—1)

This invention relates to the art of so-called crimping machines which are designed primarily for the purpose of crimping or attaching terminals to the extremities of insulated electrical conductors, the crimping affecting the terminals and insulation to positively maintain the former in position on the latter.

Electrical conductors have for a long time been provided with terminals which have been crimped thereon, with the crimping effects being evidenced only at the point where the terminal engages the metallic conductor itself. With this arrangement, the free end or skirt of the terminal extends backwardly from the insulation and among a large class of conductors, particularly those of smaller diametrical dimensions, it has been the practice to leave the terminal in this condition with only the front portion thereof crimped to the metallic conductor.

There have been certain developments in this art directed at the crimping of the skirt portion of a terminal to the insulation, but up to the present time the crimping of the skirt on the insulation has been entirely free and independent of the operation of crimping the forward end of the terminal to a conductor.

With the foregoing in mind, this invention has in view, as its primal objective, the provision of a machine which may be operated to simultaneously 30 crimp the forward end of a terminal to a metallic conductor and the skirt portion to an insulation. With this broad objective in view, this invention contemplates the provision of a machine including a plurality of movable jaws, each of which 35 is formed with projections adapted to engage both extremities of a terminal to crimp the same.

An important phase of the present invention is the design of the crimping jaws. These elements are intended for cooperation with one another 40 and when moved simultaneously under power against the terminal in which the extremity of the insulated electrical conductor is received, will crimp the forward end of the terminal to the conductor and the skirt portion to the insulation.

An important object of the present invention is to provide mechanical devices for causing a positive and simultaneous operative movement of the crimping jaws. In carrying out this thought in a practical embodiment, a bed is formed with channels in which the jaws are slidable. Spring means are availed of to maintain the jaws in their retracted position while cam devices are employed to positively urge the jaws radially inwardly of one another to provide their crimping effects.

Yet another important object of the present

invention is to provide a foot operating mechanism for the said cam means whereby the machine may be operated under the influence of the foot of an operator with the utmost ease and rapidity.

Prior to the present invention, it has been the practice to provide crimping machines of this general type with foot operated parts that are characterized by the need of the operator exerting a downward push with the foot. To the ends of enhancing the ease with which the machine may be operated and to increase the rapidity of the operation, this invention has in view the provision of a foot operated device which is characterized by a swinging movement of the part which engages the foot of an operator.

Important detailed features of the invention are associated with the provision of mechanism for operatively connecting this swinging foot operated member with the cam devices which actuate the jaws.

Other more detailed objects and advantages will in part become apparent and in part be hereinafter stated as the description of the invention proceeds.

The invention therefore comprises a plurality of crimping jaws mounted for movement with respect to each other, whereby they mutually cooperate to crimp a terminal to the extremity of an insulated conductor. Associated with the jaws, are cam devices that are operated under the influence of a novel type of foot operating mechanism.

For a full and more complete understanding of the invention, reference may be had to the following description and accompanying drawings, wherein:

Figure 1 is a view in side elevation of a crimping machine made in accordance with the precepts of this invention. In this view the base on which the machine is mounted is shown in section. This view is taken looking in the direction indicated by the arrow 1 on Figure 4.

Figure 2 is a detailed side view of the foot engaging member shown in Figure 1. This view is taken in the direction indicated by the arrow 2 on Figure 1.

Figure 3 is a detailed showing in section of the machine. This view is a transverse view taken through the pedestal and associated parts. The plane on which this view is taken is indicated as represented by the line 3—3 on Figure 4.

Figure 4 is a plan view of the machine with certain parts removed.

Figure 5 is an enlarged detailed showing in perspective of the pedestal, while

Figure 6 is another enlarged detailed perspective of the cam operating assembly.

Figure 7 is a detailed showing in perspective of one of the crimping jaws.

Figure 8 is an enlarged detailed side view, partly in section and partly in elevation, showing the position of the crimping jaws just prior to engagement with the terminal, and

Figure 9 is a view similar to Figure 8 showing the jaws in position after the terminal has been crimped.

Referring now to the drawings wherein like reference characters denote corresponding parts, a crimping machine made in accordance with the present invention is shown as applied to a table A or other suitable supporting surface. This table A may be formed with an opening at 10 through which a foot operating mechanism, to be later described in detail, may pass.

The present crimping machine comprises a pedestal designated 11 that is formed with a base 12. This base 12 has openings 13 which may be availed of to positively secure the pedestal in position on the table A. As shown in Figure 1, headed bolts 14 extend through the openings 13 and similar openings in the table top A and at their lower extremities are provided with nuts 15. As brought out in Figure 3, the pedestal 11 is of a hollow or bell-like formation and has a portion 16 that is slightly reduced in diameter as evidenced by a shoulder at 17. At its upper extremity, the pedestal 11 is materially reduced in diameter and which reduced portion is defined by a ring-like shoulder 18 that is substantially parallel to the table A. The upper reduced portion may be identified by the reference character 19.

In the form of the invention illustrated and described in this application, the crimpage of the terminal is obtained by the use of six crimping jaws. However, it is to be clearly understood that the invention is not to be limited in respect to the number of jaws employed as this number could be varied as circumstances dictate.

Bearing in mind that these crimping jaws are to be operatively included in the assembly, the upper portion 19 of the pedestal 11 is formed with six radially extending channels that are identified by the reference character 20. These channels 20 all terminate at a central point which is at the axis of the pedestal 11. Drilled substantially through the center of each of the channels 20 is an opening 21 which is of a diameter larger than the width of the channels. In view of this diametrical dimension, each of these openings 21 is shown as being evidenced in the side walls of the channels 20 in the form of notches 22.

Upon reference to Figure 3, it will be noted that the openings 21 extend downwardly into the pedestal 20 to the points where they merge with angular openings 23 which are drilled in the pedestal at the point where the shoulder 18 joins with the cylindrical wall of the reduced portion 19. Each of the openings 23 terminates in a narrow opening 24 that extends to the inner hollow of the pedestal 11. It is notable that there is one of these openings 24 for each of the channels 20. Received in each of the openings 21 is a spring member 25 that has one end offset and received in the opening 24 as indicated at 26. Each of the springs 25 extends upwardly through its respective opening 21 and has its extremity projecting into the channel 20.

Received in each of the channels 20 is a crimping jaw which is referred to generally by the reference character 27 and upon reference to

Figure 7, the construction of one of these jaws 27 is described in detail. This jaw 27 is of rectangular cross-section and the under side thereof is provided with a recess 28 which receives the projecting extremity of the spring 25. The end of the jaw 27 which is disposed at the center of the pedestal is provided with crimping points identified by the reference characters 29 and 30, that are separated by a crescent shaped recess 31, while the other extremity of the jaw 27 is formed with a cam surface designated 32 which is designed for cooperation with the cam devices to be later described. It is evident that each of the springs 25 affects the respective jaw 27 to maintain the latter in retracted position in which the crimping points 29 and 30 are drawn back and spaced apart.

Disposed about the reduced portion 19 is a ring member 33 which has a downwardly extending neck 34, the lower end of which engages the shoulder 18 while the inner peripheral surface engages the exterior cylindrical wall of the reduced portion 19. This ring 33 is formed with an extension designated 35 which constitutes an operating member as will be later described. The ring 33 is provided with six channels 36 which have their axis in substantial alignment with the respective axis of the channels 20, and received in each of the channels 36 is a cam member 37 that has a cam surface at 38 designed for cooperation with the cam surfaces 32 of the respective jaws 27.

Upon reference to Figure 6, it will be noted that these portions of the ring 33 between the channels 36 are provided with openings 39 and a retaining plate 40 is held in position on the ring 33 in clamping engagement with the cam members 37 by headed bolts 41 having nuts 42 threaded to the lower extremities. It is notable that the relative positions of the cam members 37 with respect to the ring member 33 may be adjusted and the adjustment maintained by the clamping action of the plate 40.

It is evident that upon rotation of the ring member 33, which may be caused by availment of the operating member at 35, the cam surfaces 38 and 32 cooperate to cause an inward simultaneous movement of all of the jaws 27. This inward movement is limited by the engagement of the jaws with the terminal therebetween. Movement of the ring 33 in the opposite direction is limited by the cammed ends 32 of the jaws 27 extending into the channels 36. A central cap member 43 has a lip 44 that fits over the inner peripheral lip of the ring 40, and the portion which extends downward into the ring 40 is shown at 45. This cap 43 is held in position by headed bolts at 46 which extend through openings (not shown) into the openings 47 that are formed in the reduced portion 19 of the pedestal 11. This cap portion is provided with a central opening 48 and received in this opening 48 is a guide member 49 having a flange at 50 that engages the cap member 43 about the edge of the opening 48. This guide member 49 is formed with a flared opening at 51 which is disposed above the axis of the pedestal.

Upon reference to Figure 5, it will be noted that the base 12 of the pedestal 11 is of a non-circular formation which provides a corner at 52 and this corner is formed with an ear 53 through which extends an opening 54. A pin 55 extends through the opening 54 and on its inner side is provided with a nut 56. This pin 55 is headed as shown at 75

57 and intermediate the head 57 and the ear 53, the pin 55 carries a lever arm 58 that is reduced at its upper extremity as indicated at 59. Carried by the reduced portion 59 is a roller 60 that is retained in position on the reduced portion 59 in any preferred manner as by a cotter pin 61.

The lever 58 passes through the opening 10 of the table A and at its lower end carries a foot engaging member 62. Fastened to the under side of the ring 33 is an arm 63 that has a turned-down end 64 formed with an opening 65. A coil spring 66 has one end anchored in the opening 65, and its other end anchored in a smaller opening 67 in the lever 58. This spring 15 66 serves to maintain the roller 60 in operative engagement with the extension 35 of the ring 33.

The operation of the above described mechanism may be briefly outlined by noting that upon the ring 33 being swung as far in a counter-clockwise direction as permitted by engagement of the upper cammed extremities 32 of the jaws 27 and channels 36, the jaws 27 will be retracted in the channels 20 by the springs 25. A terminal such as shown in Figure 8 and designated 68 is now inserted in the flared opening 51 with its lower end engaging the upper portion of the pedestal 11. An insulated conductor comprising a metallic conductor part 69 and insulation 70 is now inserted within the terminal 68. The position of the respective parts assume prior to operation of the machine is shown in Figure 8.

The operator now exerts pressure with his foot to swing the lever 58 which causes, through the engagement of the roller 60 with the extensions 35, rotation of the ring 33 in a clockwise direction. This rotary movement of the ring 33 causes the cam surfaces 38 to engage the cam surfaces 32 of the jaw members 27 to move the latter radially inwardly, whereupon the crimping points 40 29 and 30 crimp the material of the terminal into the form shown in Figure 9 in which the forward end of the terminal is securely crimped to the metallic conductor 69, while the skirt of the terminal 68 is crimped to the insulation 70.

An important phase of the present invention is that the crimping of the terminal in two places is effected simultaneously, thereby facilitating and reducing the cost of manufacture.

While a preferred specific embodiment of the invention is herein set forth, it is to be clearly understood that I am not to be limited to the exact constructions illustrated and described, because various modifications of these details may be provided in putting the invention into practice within the purview of the appended claims.

I claim:—

1. A machine of the character described comprising a pedestal formed with a base adapted to be secured to a supporting table, said pedestal being formed at its upper end with a reduced portion, a plurality of radially extending channels in said reduced portion, each of said channels terminating at the center of the pedestal, crimping jaws in said channels, a ring disposed about the reduced portion of the pedestal and

formed with channels, cam members in said channels, and means for maintaining the cam members in adjusted position in said channels, said cam members having cam surfaces cooperating with the said jaws. 5

2. A machine of the character described comprising a plurality of radially movable jaws, each being formed with a metal deforming projection thereon, means for maintaining the jaws in a retracted position and means for actuating the 10 jaws radially inwardly with respect to each other, said last mentioned means consisting of a ring member, cam members carried by the ring member and engaging the jaws, means for causing rotation of said ring member consisting of 15 a pivoted lever having a roller at one end engaging an extension of the ring member, and spring means for maintaining the roller in engagement with said extension.

3. A machine of the character described comprising a pedestal having a base adapted to be secured to a supporting table, said pedestal having a reduced portion formed with radially extending channels, radially moving jaws in said channels, each of said jaws having metal deforming projections thereon, actuating means for said jaws consisting of a ring member having cam surfaces engaging the jaws, said ring member having an extension extending beyond the circumferential periphery thereof, a lever pivoted to the base, a roller on said lever engaging the said extension on the ring, yielding means for maintaining said roller in engagement with the said extension, and a foot engaging operating member on the lower end of said lever. 35

4. A terminal crimping machine of the character described comprising a pedestal formed with a plurality of radially extending channels which meet in a central recess which is adapted to have an insulated electrical conductor together with a terminal introduced thereinto, a plurality of crimping jaws, there being a jaw in each of said channels, each of said jaws being formed at the end adjacent the central recess with a projection for crimping the metal of the terminal to the metal of the conductor, and with a second projection spaced from the first and adapted to crimp the terminal to the insulation, the projection for crimping the insulation being removed a further distance from the center of the central recess than the projection for crimping the terminal to the conductor. 45

5. In a terminal crimping machine for crimping terminals to insulated electrical conductors, a crimping jaw consisting of a bar having parallel top and bottom surfaces, and formed at one end with a projection the point of which lies in a plane perpendicular to said top and bottom surfaces, and a second projection, the point of which lies in a plane that is perpendicular to said top and bottom surfaces and spaced from the plane of the point of the first projection, said bar being formed at the opposite end with a cam surface. 55

JESSE M. WHITE. 65
